UNITED STATES PATENT OFFICE.

JOSEPH PRONOVOOST, OF HELENA, MONTANA, ASSIGNOR OF ONE-TENTH TO DAVID E. PRONOVOOST AND TWO-TENTHS TO N. P. SALVAIL, BOTH OF HELENA, MONTANA.

EXCAVATING-MACHINE.

1,161,337.

Specification of Letters Patent. Patented Nov. 23, 1915.

Application filed March 5, 1913, Serial No. 752,242. Renewed April 20, 1915. Serial No. 22,718.

To all whom it may concern.

Be it known that I, JOSEPH PRONOVOOST, a citizen of the United States, residing at Helena, in the county of Lewis and Clark 5 and State of Montana, have invented certain new and useful Improvements in Excavating-Machines; and I do hereby declare the following to be a full, clear, and exact description of the invention, such as will 10 enable others skilled in the art to which it appertains to make and use the same, reference being had to the accompanying drawings, and to the letters and figures of reference marks thereon, which form a part 15 of this specification.

This invention relates to new and useful improvements in ditching and excavating apparatus and comprises a simple and efficient device of this nature having various 20 details of construction and combinations and arrangements of parts which will be hereinafter fully described, shown in the accompanying drawings and then specifically defined in the appended claims.

25 I illustrate my invention in the accompanying drawings, in which:—

Figure 1 is a side elevation of the apparatus, partly in section. Fig. 2 is a plan view. Fig. 3 is an end view. Fig. 4 is an 30 enlarged detail in elevation of a part of the apparatus. Fig. 5 is a detail in elevation of the excavator scoop. Fig. 6 is a top plan view of the details shown in Fig. 5. Fig. 7 is a rear elevation of the scoop or shovel. Fig. 8 is a detail in elevation of the upper 35 portion of the tower. Fig. 9 is a sectional view through Fig. 8, showing parts in elevation. Fig. 10 is an elevation of the forward end of the boom showing the anchoring device. Fig. 11 is a top plan view of 40 Fig. 10, and Fig. 12 is a detail in section of a power transmission feature of the invention.

Reference now being had to the details of 45 the drawings by numeral, 1 designates the truck of the apparatus mounted upon suitable wheels 2 and 3, the latter of which are adapted to be driven by belted connection with a counter shaft 4 which is driven by 50 belted connection from the driving shaft 5, which in turn is driven by the engine 6 mounted upon the truck.

Pivotaly mounted upon the pin 7 is a laterally and vertically swinging pivotal 55 boom 8 having a rock shaft 9 journaled near

the forward end thereof, as shown clearly in Figs. 10 and 11 of the drawings adapting the boom to swing vertically, and fixed to said rock shaft are the spur anchor members 10, held by means of set screws 11, and 60 curved arms 12 are fixed to said shaft and are adapted to be positioned in the path of the excavator bucket 13 when the same is drawn forward in a manner presently to be described for the purpose of rocking the 65 shaft to throw the anchors out of the soil.

A cable 14 is fastened to an eye 15 upon the cross-piece 16 which is fastened to the end of the boom and passes about a pulley 17 at the upper end of the tower or mast 18. 70 Said tower has a projecting member 18^x thereon and is made up of two upright pieces, as shown in Figs. 3 and 8, and is pivotally mounted upon the pins 20, shown in Fig. 3 of the drawings. Said cable 14 winds 75 about a drum 21 about which a friction band 22 is passed, one end of which band is fastened to the angle lever 23 and in turn pivotally connected through the rod 24 with the lever 25 to which an operating handle 26 is connected. A weight 27 is fastened to a rope 28 which winds about a contracted portion 29 of the drum and serves to take up slack and keep the rope 14 taut. A sec- 80 ond or hoisting cable, designated by nu- 85 meral 30, is fastened to the outer end of the boom and passes about the pulley 31, thence to and about a winding drum 33 which is fixed to the shaft 5. The cable 30 passes about a pulley 34, journaled upon a shaft 35 mounted in the frame 36, as shown clearly 90 in Fig. 5 of the drawings. It will be under- 95 stood that the drum is allowed to revolve when the apparatus is being moved from place to place, the cable or rope first being detached therefrom.

Rollers 37 are mounted upon the shaft 35, one upon either side of the yoke 38, as shown clearly in Fig. 6 of the drawings, said rollers 37 being adapted, when the excavator 100 shovel or scoop is pulled forward, to contact with the curved arms 12 to cause the shaft 9 to rock to throw the anchors out of the ground, suitable guards 40 being adapted to guide the rollers so that they will come in contact with said curved arms 12. The frame 36 is pivotally connected to a shaft 41 connected to the arms 42, which are pivotally mounted upon the trunnions 43 project- 105 ing from the opposite sides of the scoop. A 110

- suitable strut 42^x connects the scoops with the frame 36, serving to hold the bucket in different adjusted positions. Said scoop has a plow 44 fastened to its lower end and 5 adapted to scoop up the loosened soil and also a sub-soil loosener or plow 45, having shank portions 46 which are bolted or otherwise secured to the scoop and which extend below the bottom of the shovel or scoop and 10 loosen a new supply of dirt after the scoop has been moved forward with its load. Said scoop or shovel has arms 48 which are hinged at 49, forming means for dumping the load when elevated to proper position. 15 The back 47 of the bucket is provided with a sliding latch 50 which, as shown in top plan in Fig. 6, has ears 51 projecting therefrom, and 52 designates a depressable member having pivotal connection at 53 with the 20 ears 51 and its lower end is fixed to a spring 54, shown clearly in Fig. 7 of the drawings, the ends of which spring engage the laterally projecting lugs 55 upon said back. Said latch 50 engages a hole in the plate 57 25 and serves to normally hold the back closed.

Curved members 58 are fastened to the back, as shown clearly in Figs. 6 and 7, and serve as means to protect a scoop when the latter comes in contact with the ground when 30 lowered and also as a means for throwing the hopper 60 laterally out of the way of the scoop as the latter is lowered and after the load has been dumped. Said hopper 60 is pivotally mounted upon the shaft 61 carried 35 by the tower and its lower end normally engages the chute 62 in readiness for receiving the load as it is dumped from the scoop. Anti-friction rollers 63 are mounted at the angled ends of the hopper which are adapt- 40 ed to contact with the curved members 58 after the scoop or shovel has been dumped and is being lowered to the ground. Fig. 4 of the drawings illustrates the hopper thrown laterally in order to allow the scoop 45 to lower to the ground. In order to hold said hopper in the proper position while the scoop is being dumped, the locking bars 65 are pivotally mounted upon the shaft 66 and are pivotally connected by means of the bars 50 67 with the shaft 68 carried by the hopper 60.

The means for imparting a lateral swinging movement to the boom 8 consists of the chains 70 which are connected each to the 55 cross beam 71 upon either side of its pivotal point 7, said chains adapted to wind upon the drum 74 to which drum a worm wheel 75 is fixed which is in mesh with a worm 76 fastened to the shaft 77, having a hand 60 wheel 78 for operating the same. The shaft 77 has a bearing eccentrically within the block 79, the latter having a circumferential bearing 80 turning in an annular groove 81 formed in the member 82. A hollow 65 shaft 83, through which the shaft 71 passes,

is fastened by means of a set screw 84 to the bearing block 79 and a hand wheel 85 serves as a means for rotating the hollow shaft 83, accordingly as it may be desired to throw the worm wheel 76 into or out of 70 mesh with the worm wheel 75 or worm wheel 86, which latter is fixed to the shaft 87 mounted in suitable bearings upon the truck of the apparatus.

Chains 88 are fastened to the shaft 87 and 75 are secured to the forward axle 89 of the truck and form means for steering the craft when it is desired to move the apparatus under its own power.

The operation of my invention will be 80 readily understood and is as follows:— When the boom drops by gravity to the position shown in Fig. 1 of the drawings, the anchor spurs will engage the ground and securely hold the boom in the positions illustrated. By winding the cable 30 upon the drum 33, which drum is driven by the engine, the scoop will be drawn forward and receive its load. As the scoop approaches the curved arms 12, the scoop will be guided 85 by means of the guards 40 so that the rollers 37 will come in contact with said curved arms 12. A further forward movement imparted to the scoop will cause the shaft to which the curved arms and anchor spurs are 90 secured to rock, thus disengaging the same from the ground and a further pulling movement upon the cable 30 will cause the boom to swing upward and assume the position shown in dotted lines in Fig. 1. As the 100 scoop reaches its highest position, the cross-piece 16 at the end of the boom will pass underneath the pivotal bars 65, which will hold the hopper 60 in position to receive the load as it is released from the scoop. Simul- 105 taneously with the passage of the upper end of the hopper underneath the levers 65, the head of the member 52 will come in contact with the projections 18^x upon the tower and cause the retaining slide 50 to move longitudinally against the tension of the spring 54 and which will release the end gate of the scoop and allow the load to be dumped. After the load has been dumped, the operator by manipulating the friction brake 22 110 115 may give slight slack to the cable 14, which, with the drum, holds the scoop while the latter is being dumped, sufficient to allow the scoop to lower to clear the retaining levers 65 and, upon lowering the scoop further 120 through the medium of the cable 30, the curved members 58 coming in contact with the rollers 63 will cause the hopper 60 to swing laterally, as shown in Fig. 4, and out of the path of the scoop, allowing the latter 125 to again lower by gravity to the ground to receive a new load. After the scoop reaches the ground, the boom swings down by gravity and the momentum of the boom as it approaches the earth will cause the anchor 130

spurs to engage the ground and securely hold the same. It will be noted that, when the scoop is drawn forward to receive its load, the sub-soil plow will loosen the material for the next load. In the event of it being desired to cause the boom to swing laterally, it may be done through the medium of the hand wheel 78 and connections. By the provision of the hand wheel 85 and its 10 connections, the forward axle of the truck may be turned in one direction or the other for the purpose of guiding the apparatus when it is driven under its own power from place to place, the engine serving as means, 15 through the belted connections shown, for driving the rear axle of the truck.

By the provision of an apparatus embodying the features of my invention, it will be noted that the operation is continuous by 20 first drawing the scoop through the soil, elevating the same, lowering and dumping and again repeating through continuous cycles.

What I claim to be new is:—

1. A ditching and excavating apparatus 25 comprising a truck, a tower mounted thereon, a pivotal boom mounted upon the truck, means for swinging the boom, a rock shaft upon the latter, an anchor member fixed to said shaft, releasing arms projecting from 30 the rock shaft, a scoop, pulleys upon the

boom, tower and scoop, a winding drum, a cable passing about the latter and said pulleys, means upon the scoop for causing the same to engage said releasing members as the scoop approaches said members, the 35 scoop and boom adapted to be raised together to upright positions.

2. A ditching and excavating apparatus comprising a truck, a tower mounted thereon, a pivotal boom mounted upon the truck, 40 means for swinging the boom, a rock shaft upon the latter, an anchor member fixed to said shaft, releasing arms projecting from the rock shaft, a scoop, arms projecting therefrom, a pulley mounted upon the latter, anti-friction rollers upon either side of the pulley, guard members adjacent to said rollers adapted to cause the rollers to contact with said releasing members as the scoop approaches the latter, pulleys upon 45 the boom and tower, a winding drum, a cable passing about the same and said pulleys.

In testimony whereof I hereunto affix my signature in the presence of two witnesses. 55
